SUBSTATION TELEPHONE SET

Ajoy Kumar Ghosh, Calcutta, India

Application January 14, 1937, Serial No. 120,542
In Great Britain February 3, 1936

2 Claims. (Cl. 179—7)

This invention relates to call registering substation telephone sets.

It has been a common practice hitherto to install call registering meters at the exchange no matter what system is used corresponding to each of the subscribers' lines, in the case where the subscribers are charged at the message rate principle. These meters are at the exchange, and with the exception in the case of automatic systems, for example in mechanical switching systems, when calls are made by the subscribers, the calling subscribers' meters are actuated by an electric impulse given by the operator at the exchange. It is claimed by telephone administrations that the meters are actuated only in the cases of effective calls and not in the case of ineffective calls, such as "no reply," "engaged," "wrong connections" and in cases of "line out of order," "service discontinued," "number changed" and the like. In the automatic system however, the meters record the number of calls quite automatically. At the end of every month, whatever be the system, automatic or manual, meters are read and bills are made out according to the rates fixed.

There are numerous types of exchanges in different countries working on different systems: such as magneto system, common battery system (usually termed C. B. system), semi C. B. system and other systems which are all manual exchange systems and again there is the automatic exchange of which alone there are several systems. The telephone instruments are generally required to be of different mechanism to suit different exchange systems. The present invention is primarily concerned with the telephone instruments at the subscribers' end, and here mainly deals with the commonly adopted system, which is an up to date C. B. system with lamp indicator.

The call counting system, as now existing is absolutely non-automatic, and from the subscriber's point of view there is left sufficient room for doubt as to the number of calls recorded by the exchange operators, as the public cannot know to their satisfaction, whether the differentiation between effective and ineffective calls is correctly made in each and every case and whether the meters are unnecessarily advanced by the interested party. Another disadvantage of the existing system is that the subscribers cannot have any definite idea of the progress of calls during the month.

The present invention relates to arrangements comprising a meter at the subscriber's end of the

line and its principal object is to provide a telephone instrument embodying a combination of features which will not only enable the whole operation of call-registering to take place before the eyes of the subscriber so as to leave no room for suspicion between the public and telephone administrations, but will also enable unauthorized or undesired use of the instrument to be prevented so that the meter shall not be advanced for example in the subscriber's absence.

According to this invention, a telephone instrument is provided with a meter at the subscriber's end of the line for registering outgoing calls, means for advancing the meter by one unit before the instrument can be connected to the exchange for the purpose of effecting an outgoing call, means for retracting the meter by a unit when the call is ineffective and means being provided for the automatic circuit breaking of the armature (of the meter) when the latter is attracted by the electromagnet (of the meter) and further means by which the armature is retained in this attracted position as hereafter described.

By means of this invention it is possible to simplify to a great extent the call recording work on the part of the exchange operators as well as to dispense with elaborate call recording equipments at the telephone exchange. The administrations will however have the meters read by their men, every month, from each subscriber's instrument. In addition the instrument is easy to manufacture and necessitates no large alteration in adapting the invention to existing installations. Also a subscriber may detect from the meter to what extent his telephone has been used in his absence and moreover if the subscriber desires he may prevent advancement of the meter by locking the meter controlling rod.

The invention also suitably provides means for indicating whether the line circuit is in order when the receiver is lifted as well for preventing accidental advancement of the meter when conversation is going on. Means may also be provided for effecting flashing independently of the hook or cradle.

It is known in the C. B. system for provision to be made for electrical indications, for example the production of a typical buzzing note in the ear-piece termed "busy tone" denotes "engaged" and a like tone serves for "no reply" such as is obtained in the automatic telephone system. But as in many cases the public are not

accustomed to such indications, the operators are generally required to inform them orally. It is quite possible to educate the public to these indications and to adopt the electrical indications exclusively so that the operator at the exchange will have no necessity of uttering "no reply" or "engaged."

Within the instrument a meter is provided along with such mechanism that correct recording of calls will be evident when the instrument is desired to be used for sending out calls and further in case of an ineffective call, which has already been recorded in the meter, the stepping back of the meter reading by a unit by the subscriber himself can be effected by suitably utilizing an electrical impulse provided from the exchange to signify such ineffective call, which means the same meter will tick back one unit. The quality and/or character of the impulse can of course be modified, as desired.

Now for stepping back the meter, the utilisation of the electric impulses, given to signify ineffective calls, will be easily possible, provided a steady impulse can be compounded or included with the tone signal impulses. For retraction of the meter however an impulse has to come in all cases from the exchange; and it is best and simplest to provide the steady impulse side by side with the busy-tone as in that case nothing remains to be done separately on the part of the operator for the meter retraction; whereas it would be to the interest of the subscriber to get his due refund by utilising the impulse as soon as available. One way how the busy-tone and the impulse can be compounded is herein-after described.

Also in case of ineffective calls like "number changed," "service discontinued" or the like where the busy-tone is not provided and where therefore oral information of ineffective calls is necessary, there will be in the instrument such provision that the operator of the line at the exchange can supply the necessary electric impulse to the line on getting an indication by the supervisory lamp; by means of this impulse the meter can be stepped back by one unit. Further there are suitably various mechanical safeguards explained hereinafter which are provided so that neither party can work the meter to the other's disadvantage.

It is important also to note that the percentage of ineffective calls is far less, if not insignificant when compared with the percentage of effective calls, and again the number of "no reply" to calls is much less than "engaged" while "wrong connection" is found fairly frequent due to many reasons, and the chance of this falling into the class of ineffective calls is very small because it becomes ineffective only in the case of the right number, next informed, being reported as "engaged" or "no reply." It has been found that "engaged" covers the greatest volume of ineffective calls. And again those ineffective calls other than "no reply" and "engaged" do not occur more than once or twice per month per subscriber on the average. Only in case of the latter type of ineffective calls, will it be the duty of the operator to utter some word, say "retract," along with what is usually uttered to signify those ineffective calls. The subscriber will then push only once a certain knob of the instrument to its full extent when the supervisory lamp will be only once "on" and again "off" and nothing more, and then the operator at the exchange will press a key by which

5 a suitable electric impulse can be given to the subscribers' line, whereby the meter will be set back by one unit only.

There is, however, no need of setting back the meter in case of wrong connections until the corrected number is found to be "no reply" or "engaged." Therefore particularly "wrong connection" does not necessarily come under the ineffective calls. The matter of setting back the meter for the greater number of ineffective calls is as far as the exchange is concerned automatic, and the rest, although negligible, is under the control of the exchange operator. The registering of the effective calls is entirely automatic. 10 Nobody can or will ordinarily tamper with the meter reading mainly because of the mechanism adopted, and secondly because it is distinctly against the interest of the parties concerned. The meter therefore works impartially and correctly before the eyes of the subscriber.

15 It may be mentioned here that like registering, the stepping back of the meter can be entirely automatic as far as the exchange is concerned and can be freed from anybody's control if exclusively electrical indications for every class of ineffective calls is introduced. There is also provision made in the instrument whereby the called subscriber cannot claim for retracting the meter. Therefore any claim for retracting 20 the meter must come from the calling subscriber only. Thus the chance of a fictitious claim for refund is at once removed. Therefore any complaint from the subscribers' side regarding the setting back of the meter, can be generally taken 25 by the authorities as true and can be mostly settled then and there if found correct in favour of the subscriber by supplying an impulse. Otherwise the number of such complaints as are disputed can be noted down and if decided 30 in favour of the subscriber can be deducted from his monthly bill. Also the work of the operator is considerably reduced by automatic recording, and the work of setting back the subscriber's 35 meter is mostly automatic, the operator's duties will be very much less, than under existing conditions and therefore the occasional duty of providing the necessary electric impulse for setting back the meter will not be neglected due to 40 flashing as this will be noticed by the supervisor.

45 50 In applying the invention to the existing type of up to date C. B. telephone instruments, there is provided an ear-piece and a microphone as well as an induction coil, one polarised electric ringer with a condenser in series and one switch, 55 which works automatically by the up and down movement of the hook or cradled due to lifting and replacing of the receiver handle or the receiver microphone handle where both are combined. For convenience both receiver handle 60 and receiver-microphone handle i. e. hand-microphone-telephone, will hereinafter be indicated by the word "receiver."

65 Generally, the cradle for the last-mentioned type of receiver, stands outside a casing which has a hole or holes at the top of it for the passage of the cradle stem, and this casing encloses all the other portions of the instrument inside. A two wire telephone line from the exchange enters into the instrument and is connected with 70 the ringer through the condenser as well as to the receiver through a switch placed in series, which switch remains broken when the receiver is on the cradle. On lifting the receiver the connection of the line with the phone circuit 75 is established and the supply of ringing current

i. e. alternating current, if any at that time, is stopped by a relay at the exchange when the called subscriber lifts his receiver.

The instrument according to the invention in addition to the parts of an up to date C. B. instrument, is suitably provided with certain mechanism hereinafter explained, wherein are two knobs each operating a rod projecting outside the casing.

A meter and if desired a glass window for reading the meter are also provided.

The meter is operated through one knob and the other knob operates or controls, when turned or pushed as may be required, a reversing arrangement for stepping back the meter by a digit as hereinafter explained.

The arrangement for stepping back the meter is electrically controlled from the exchange either automatically or by the exchange operator; moreover, the mechanism of the meter is such that the meter can only be set back one unit at a time and a typical tone gong is provided worked by the armature of the meter to give a sound at the time of each reversal of the meter. There is an indicator to give a test of the line before operating the meter. A horseshoe-magnet or electromagnet with a soft iron armature is also provided which controls a switch placed in series with the phone circuit. Further, there is a contrivance for drawing the attention of the operator by means of the line lamp or supervisory lamp as the case may be which is done at present in the ordinary instruments by moving the hook or cradle up and down. The function effected by moving the hook or cradle up and down is effected according to this invention by means of the second knob which when pressed operates a mechanism to cause the necessary break and make of contacts to the line wire giving necessary indication by flashing. Several safety locking contrivances are also suitably provided, as hereinafter described.

It is to be understood that the whole instrument with the component parts and connections excepting the receiver and microphone and the hook or cradle, may be mounted and entirely enclosed, in a suitable box which can be properly sealed at its opening side to avoid or to detect any tampering inside. The meter reading and the indicator are suitably visible from outside through glass windows which are provided. At the two sides of the box there will be provided two holes through which the two knobs previously referred to project outside the instrument. The placing of the two knobs for appearance can be shifted to any convenient position of the instrument, with corresponding changes in the position of the mechanism inside, necessary for such shifting. Also, if desired the movable parts may be adopted to limit or increase the play of connected parts to the required extent through means such as levers or otherwise.

The invention is illustrated in the accompanying drawing which is a diagrammatic view of the instrument according to the invention.

In the drawing:

1 is a receiver cradle with a stem 2 having four stops or pins 3, 7, 4 and 5 horizontally fixed to the stem 2 and insulated from it. The pin 5 projects on both sides of the stem and a hole 6 is provided across the stem 2. A bracket or platform 8 with two holes in it is suitably fixed to the casing and the platform 8 supports a suitable spiral compression spring 9 located over it. The stem 2 passes through the spring 9 and one

of the holes in the platform 8 and rests on the top of the spring 9 by its pin 5 and as a result, the cradle 1 has a tendency to move up, but is lowered by the weight of the receiver 1a when the latter is placed over the cradle 1. A metal piece 10 with a metal knob 11 fixed at its top rests over a spring 12 fixed on a bracket 12a.

An extension rod 11a is fitted and fixed to the bottom of member 10, the rod 11a passes through the bracket 12a, and also passes through the other hole in the bracket 8.

The lower bent end of rod 11a presses over the end of a lever 57, and the other end of lever 57 enters into the hole 67a in rod 41, when the member 10 reaches its lowest position.

The adjustments of the lever 61 controlling the rod 65 and the adjustment of the control of lever 57 is such that 57 locks 41 after 65 is pulled out of the hole or recess 67 by lever 61 during the downward movement of stem 2.

On the rod 11a is a pin 109 which extends over and controls the spring strip 110. When 10 rises to close the switch 13, then 11a also rises and so releases the lever 57. The other end of lever 57 now drops out of the hole 67a by its own weight and releases rod 41.

Further the rod 11a passes between the knives of switch 23a without touching them. 11b is a metal bush fixed to rod 11a and insulated from it.

The position of 11b is such that it closes switch 23a when 10 rises and closes switch 13.

The wires 81 connects up a call-registering meter 23 through the switch 23a.

The metal piece 10 can only move up with the stem 2 on removal of both the restraints of the projecting pin 3 and rod 14. When the receiver 1a is taken off the cradle, and when metal piece 10 moves up, it establishes an electrical connection by knob 11 at switch 13. A horizontal rod 14 mounted in a bracket 14a is fitted with a spring 15, and normally tends to project over the horizontal surface 21 of piece 10 to keep the latter depressed, as also is done by pin 3 when the receiver is on the cradle 1. Rod 14 can be moved back to release piece 10 by the longitudinal movement of the meter-advancing rod 16 when the latter is pressed by its knob 17. The rod 14 engages with rod 16 by means of a vertical lever 18 having a fulcrum at 19. Either rod 14 or pin 3 of the stem 2 or both, will prevent metal piece 10 from rising up and forming connection at the switch 13; pin 3 releases its restraint on metal piece 10 when the receiver is taken off the cradle 1.

The piece 10 has a smooth bevelled edge 20, and when the end of the rod 14 reaches the bevelled edge 20 its further movement causes the piece 10 to be forced down till 14 extends over the horizontal surface 21, thus locking piece 10 and cutting off switch 13. It is to be noted that until pin 3 has first sufficiently depressed piece 10, the rod 14 will not act, as the rod 14 will not reach the bevelled edge 20.

It should be further noted that the switch 13 does not lose connection until the rod 14 reaches say half the height of the bevelled edge 20. Further as rod 14 reaches the bevelled edge 20 the action of the spring 15 on rod 14 will cause 10 to be pressed down to its full extent thus locking 10 in position leaving switch 13 disconnected. The switch 13 therefore can be cut off by the subscriber but cannot be reconnected until the meter is again advanced by rod 16.

It is to be noted that the spring 15 is of such

strength that it can work against springs 12 and 110 to depress member 10, till rod 14 extends over the horizontal surface 21, when 14 reaches the bevelled edge 20. The inner end of rod 16 will just touch the stem 2 of the cradle 1 when the receiver is on the cradle. The knob 17 cannot be pushed in at all until the receiver is taken off, and the hole 6 in the stem 2 is in alignment with or level with the rod 16.

Now the rod 16 tends to move, due to a spring 22, in the direction as shown by the arrow 22a, and metal piece 10 can only be released to close the switch 13 when two conditions are satisfied simultaneously, firstly when the receiver is taken off the cradle 1 and secondly when rod 16 is pushed through hole 6 to operate the lever 18 to cause rod 14 to release metal piece 10; such connection of switch 13 will enable the subscriber to get the exchange, as the line lamp is lit by the connection of the switch 13. In addition to operating rod 14 through lever 18 there is a further function effected by rod 16. Before rod 16 operates lever 18 to release metal piece 10 it has to actuate a ten toothed ratchet wheel 24 of the call-registering meter 23 by a spring controlled pawl 25 attached to rod 16. This movement of the ratchet wheel 24 due to pushing in of rod 16, advances the meter 23 by one digit at its unit place and thus the meter records a call or rather a connection with the exchange. 23 is a type of counting meter having for example four digits and is therefore able to record up to 9999 i. e. practically 10,000 calls. The meter is advanced by manual power, as already explained and can be stepped back by electric impulse. The stepping back is effected by another similar ratchet wheel 24a fixed to the same axle as the wheel 24 but having its teeth inclined in an opposite direction and operated by the movement of a spring pawl 26 fixed to the armature 27 of an electro-magnet; the latter being worked by electric impulse given to it. Thus the meter can also be set back by one unit when necessary. In addition to this setting back of the meter the armature 27 cuts off a connection of the switch 29 placed to series with the meter and at the same time strikes a gong 27b by the hammer 27a fixed to the armature 27. Thus when the meter is stepped back, a sound is obtained additionally. The armature of the meter retracting an electro-magnet is not controlled by a spring and therefore the connection of switch 29 cannot be re-established automatically. In this way the retracting of the meter more than one unit by several electrical impulses at a time is prevented, and further in addition there is fixed a permanent magnet 30 preferably a horse-shoe magnet, but of course in such a position and at such a distance that it does not appreciably interfere with the useful or effective lines-of-force of the retracting electro-magnet of the meter i. e. does not affect the function of the latter magnet when same is excited. The horse-shoe magnet 30, through its armature 69 mounted on an extension rod 270 of the armature 27 of the meter retracting electro-magnet holds such armature 27 in the attracted position of the electro-magnet. Thus when the electro-magnet is out of action after retracting the meter, the permanent magnet 30 due to the magnetic contact with the armature 69 does not let the latter drop on the switch 29 to form a connection even if the whole instrument is tilted and a jerk given. This prevents the meter of the instrument from being fraudulently

retracted by local impulse by any enterprising subscriber.

It should be noted that the weight of the armature 27 is such that when it is at the farthest end of its stroke from the electromagnet 28, it cannot turn the wheel 24a by its pawl 26 when the instrument is tilted or shaken. Further to prevent any possibility of tampering like this a pawl 26b may be hinged to and freely suspended from a suitable position in the casing in the same plane as and close to the wheel 24; so that if the instrument is tilted, the pawl 26b will swing over a tooth of the ratchet wheel 24 arresting any clockwise rotation of the ratchet wheel 24a. Ordinarily however the pawl 26b has no function.

When the meter is once retracted it can only be made fit for another retraction after the meter has been advanced again by rod 16, whereby the armature 27 will take its former position due to the lever 31 attached to rod 16 and pivoted at 31a striking the rod 270 and pulling the armature out and forming the connection at switch 29.

32 is the usual polarised electric ringer working on A. C. both ends of which are connected to the line and which is provided with a condenser 33 in series. 34 is an automatic control for switch 35 and consists of a horse-shoe electro-magnet 34a having its armature 36 pivoted at 36a. The cores of both 32 and 34a have brass points on them to avoid magnetic contact with their respective armatures. The armature 36, due to a spring 36a at its pivoted end, ordinarily keeps away from the magnet as shown and the other end of the armature is pointed.

Now 34 is connected with 32 in parallel and therefore this combination of 34 and 32 is in series with the condenser 33, before mentioned. Without however combining 34 and 32 and putting one condenser only, they can be independently joined up with the line having one condenser for each in series. The construction and the resistance of the windings of the electro-magnet is such that the strength imparted to the electro-magnet or control 34 is sufficient not only to attract the armature 36 by the usual ringing current, but is also sufficient to attract it down even if some pressure is exerted by bar 40 on its head; but any current of lower intensity than the usual ringing current such as may be generated during the working of the indicator, explained hereinafter, will not be sufficient to attract down the armature 36 and more so when pin 40 presses over 36, even if the ringer 32 responds. A slight tapping of the cradle just at the moment of ringing but not during the interval of ringing will easily allow the armature 36 to be attracted down by the control 34. In this case the special construction and winding of the control 34 as suggested above may be unnecessary.

37 is a metal rod for closing the switch 35 and moves horizontally; within a fixed tube 38 open at both ends. The rear portion of the rod 37 protrudes out of the tube 38 and to this portion is hinged one end of an L-shape lever 39. The rod 37 has always a tendency to close the switch 35 due to a comparison spring (not shown) housed inside the said fixed tube 38, but when the whole instrument is at rest, it is prevented from so doing in two ways; firstly, due to the pin 4 of the stem, pressing on the lower arm of the lever 39 and secondly, due to the obstruction caused by the armature 36 to the bar 40 projecting downward and which is fixed to rod 37. The lower end of the bar 40 extends to such a level that if the

armature 36 is attracted down, bar 40 is no longer obstructed by the armature 36.

At the time of sending out calls the receiver is taken off the cradle, but although the lever 39 is thus released, the rod 37 is still prevented from closing the switch 35 due to the armature of 36 obstructing its bar 40 and to get the exchange, the switch 13 must first be closed by pressing knob 17 of rod 16 and thus releasing metal piece 10 as already detailed. When receiving calls the ringer 32 will first ring and as control 34 is connected with 32 in parallel, the armature 36 will also be attracted at the same time, and now the cradle 1 being lifted due to the removal of the receiver according to the general practice, the lever 39 is also released; and the rod 37 being freed from both its obstructions simultaneously, will at once proceed to close the switch 35 and the line now comes to the phone circuit and due to a relay at the exchange, both 32 and 34 will be put out of action. When the conversation is over, and the receiver replaced, the lever 39 is pressed by pin 4 and the rod 37 is pulled out of switch 35 and the armature 36 also being released, springs back to its previous position.

It should be understood that the release of the armature 36 must not take place after 37 is pulled out of the switch 35, otherwise it would be possible to partially depress the cradle and make a fraudulent call through the switch 35 by again releasing the partly depressed cradle. The construction of the knob of rod 37 and of the tips of the switch 35 is such that when the rod 37 is pulled, the tips will yield to some extent say 3 or 4 millimetres, due to friction, and after that limit they will retract to break connection, thus delaying a little the opening of the switch 35. Therefore during this pulled-out stage of the tips of the switch 35, the armature 36 will spring back to its previous position to lock 40. The tips of the switch 35 can, while 37 is pulled, extend forward a little but cannot be pressed backward when the knob of 37 jumps between them to establish connection. The same effect may be achieved by mounting switch 35 on a spring holder. The closing of the switch 35 must also be effected like the breaking in an abrupt manner, and any known means may be employed for this purpose. Instead of arranging 37 to proceed forward only horizontally it is also possible to make 37 ride a short inclined cam while proceeding forward and drop within the grip of 35, where the cam ends. In that case the armature 36 may be arranged to play horizontally. When receiver is replaced, 37 recedes horizontally and finally slips out from under the said cam.

Ringing of the C. B. telephone bell is generally made intermittent; the reasons being that the intermittent ringing is more effective and less annoying than a continuous ring and also this economises electric current. Further, the ringing takes place say for a period of one second, at intervals of two seconds and this is also made to vary according to "load." Now the armature 36 will also remain attracted for one second and released for intervals of two seconds. If the receiver is taken off the cradle during such interval, the bar 40 will press against the head of 36 and the connection in the switch 35 will take place as soon as the next ringing starts, i. e. as soon as the armature 36 is attracted. If desired this period of two seconds of no response can be easily further lessened by further shortening the interval of ringing, i. e. by suitable adjustments in

the interrupter or machines used in the exchange for intermittent ringing purposes. For outgoing calls, therefore, the switch 13 must first be closed and consequently the call must be recorded, and for incoming calls the switch 35 will automatically work without any recording in the meter.

Again there is very often found, for various reasons, the necessity of drawing the attention of the operator and this is effected in known constructions by moving the receiver cradle 1 up and down causing what is termed flashing. This flashing takes place at the exchange switch board in the line lamp or supervisory lamp as the case may be, due to the tapping in the subscriber's instrument. By pressing the cradle line lamp is "off" and by releasing "on" and when supervisory is to function "on" and "off." In this instrument there is provided a separate contrivance for this purpose, and the cradle 1 must not be tapped as is done according to the present practice, as otherwise this will cut off the connection as if the conversation were duly finished, and then the connection cannot be re-established without actuating the meter again. This tapping is done in the present invention by a push rod 41 and the object of its mechanism is four fold. Firstly, it serves the purpose of flashing, secondly, it does not allow the subscriber to operate the lamp indicator (or rather cause interruption to the line by breaking the circuit) for more than a short period say half-second; thirdly, the push rod 41 works another mechanism 55, when necessary, to get the meter set back in case of ineffective calls when informed orally and fourthly, push rod 41 without being pressed can be turned to get the meter set back when the ineffective calls are indicated electrically. Now push rod 41 has one end which ends in a knob 52 projecting outside the instrument and the other end is flattened. There is in push rod 41 a groove 42 along its length and the length of the groove is equal to the maximum horizontal play as may be necessary for push rod 41 and also there is a groove 43 commencing from one end of the straight groove 42 and continuing up to say one-third of the circumference of rod 41. The combination of 42 and 43 therefore resembles an L cut groove which is say 2 mm. deep. In normal position of rod 41 a pin 44 which is fixed to the casing of the instrument, is located in the junction of the grooves 42 and 43 so that when rod 41 is pushed, the rod 41 cannot be turned; similarly when rod 41 is turned, the same cannot be pushed. The rod 41 works on a spiral compression spring 45 but one end of the spring wire 46 is fixed to push rod 41 and the other end is attached to the support 53.

By this arrangement the spring 45 can be compressed and released, and also some torque can be given to it when necessary. Hence push rod 41 can be either pushed in or turned round and is able to regain its original position when released as the torque in spring 45 if the rod is turned, returns it to a position where 44 will be located at the junction of the grooves 42 and 43.

The parts 46 and 47 are operated by the push rod 41. 46 is a lever perpendicularly fixed to its horizontal fulcrum member 49 and member 47 is parallel to the rod 41. On the member 49 there is another smaller lever 48 perpendicularly fixed to it, such that if the lever 48 is moved by its upper end in the direction of the length of rod 41 the upper end of the lever 46 will get a rotating movement. The upper end of lever 46 is hinged with suitable plug to the end of rod 47 which

has a metal piece 50 at its other end for closing the switch 51. If the knob 52 is pushed in, the lever 48 on the member 49 will be moved by a spring pawl 53a fitted to rod 41 and which normally touches near the top end of 48 and consequently lever 48 will move rod 47 so that piece 50 will break the connection of switch 51. But as the pawl 53a can give only a tangential movement to the top of the lever 48 while pushing the knob 52, a position will be reached when 48 will automatically be released and due to the spring 47a the rod 47 will also return to its original position and the switch 51 will again be connected by metal piece 50, whether rod 41 returns by that time to its original position or not. This can be repeated if necessary. Again the pawl 53a and the lever 48 in addition to their mechanical function, can mutually establish an electrical connection when they are in contact. The pawl 53a and the lever 48 are insulated from the members to which they are attached. In addition to the other connections at the switch 51, one end of the switch 51 is connected to the pawl 53a by wire 90 and the other end of switch 51 is connected to the lever 48 by wire 91.

Flashing is effected thus; when the knob 52 is pressed although the connection of switch 51 is broken due to receding of rod 47 and piece 50, still another connection prevails by the contact between the pawl 53a and the lever 48. The rod 41, when its knob 52 is sufficiently pressed, will release the lever 48, and rod 47 will spring back to close the switch 51; thus within the period of releasing the lever 48 and the reaching of rod 47 to close the switch 51, the switch 51 remains open for a short period and during this period the line will be interrupted and if the line-lamp is to function it will be "off" and if supervisory lamp is to function it will be "on." Therefore, on each tapping of the knob 52 the line lamp is "off" and again "on" or alternatively when the supervisory lamp is to function instead of the line-lamp, the same will be "on" and "off" automatically; and the process can be repeated over and over again if required. The timing gap can be adjusted by properly selecting the strength of the spring 47a or by some escapement device or by other means so that the opening and closing of the switch 51 cannot be too rapid, as in that case the lamp indication may not be sufficiently effective. To what limit the knob 52 has to be pressed for the indication in question, will be ascertained in the subscriber's earpiece by clicks due to the make and break, as well as a further indication at the time when the pawl 53a releases the lever 48 as at this time the flattened end of rod 41 will touch the flattened end of rod 55 which is held in position by a compression spring 92 which is stronger than 45. With some further pressure therefore on the knob 52 the rod 55 can also be pressed. Now the other end of the rod 55 is a metal knob 55a which can close the switch 56 placed in series with the switches 23a and 29, but the spring 92 always tends to keep rod 55 away from the switch 56.

A lever 58 of a similar nature to 39 already described, operates the switch 60 but there is a difference in the construction of the two levers in that the spring action of the lever 58 is in the opposite direction to that of 39 and therefore the knob 58a of lever 58 always tends to break the connection of the switch 60 and further there is no bar corresponding to the bar 40 aforesaid. The lower arm of lever 58 rests normally over the flattened end of rod 55. So long as the lever 58

rests over the flattened end of rod 55, the switch 60 is kept closed, as the knob 58a of lever 58 cannot recede. When the rod 55 is pushed by knob 52 which is only possible when calls are made i. e. when rod 11a rises to release the lever 57, the connection of switch 60 is not only broken but also rod 55 is locked in the pushed-in position by the lower arm of lever 58 falling and functioning like a pawl, moreover the switch 56 will remain closed, even when rod 41 is released. It will be understood that the switch 56 must be closed simultaneously with the locking of rod 55 by lever 58 and alternatively the switch 56 may be positioned adjacent to the lever 58 so as to be closed directly by said lever 58 in which case the knob 55a is unnecessary.

There is again a three arm lever 61 which enables the lever 58, rod 55 as well as member 65 described later to be brought back to their original position, i. e. to close the switch 60 and open the switch 56 and further when necessary, to open switch 64 and close switch 63. Further the pin 5 of the stem presses on one end of an arm of the lever 61 when the receiver is replaced and in consequence the lower arm of lever 61 pushes the lever 58 and consequently the knob 58a into the switch 60, and at the same time releases rod 55 which disconnects switch 56 and further the third arm of lever 61 lifts when necessary the member 65 which is the control of switches 63 and 64.

The member 65 is a rod shaped like an inverted L, and is placed vertically over rod 41 and is controlled by a spring 66 due to which member 65 presses on rod 41. In alignment with the lower end of member 65, is the hole or recess 67 in rod 41, into which fits the end of the member 65, and the recess 67 is in coincidence with the lower end of member 65 only when rod 41 is say quarter turned from its normal position. There is a thick metal bush or collar 68 fitted to member 65 and insulated from it, or preferably member 65 itself is of insulating material and merely for adding strength both ends of 65 may have metal mountings. When member 65 is resting on rod 41 but not within recess 67 the switch 63 gets connection by pressing over or being in contact with the metal bush 68 but the switch 64 does not get any connection as the latter gets connection only when member 65 descends into the recess 67, while the switch 63 then loses connection. The length of the metal bush 68 and its mounting on member 65 is such that during descent of member 65 into the recess 67, the switch 64 gets connection just before switch 63 loses connection, because if there be an interval, the supply of busy tone impulse may discontinue.

The construction of the switch 29 requires to be somewhat different from that of the other switches in the instrument, although some of the other switches can be replaced by a switch of type 29 to serve the same purpose at their respective positions. The switch 29 has two soft contact springs 93, 94 of metal and these two springs obtain connection by the armature 69 which is a metal plate or strip and is mounted on the extension rod 270 of the armature 27 as aforesaid. The plate 69 is advanced by the lever 31 towards the spring points of switch 29 and pressed over the two points due to pushing the knob 17 to actuate the meter, after retraction the armature 27 moving at the same time. The springs 93, 94 of switch 29 are so soft and the weight of the armature 27 along with its

extension rod 270 and plate 69, although light, is such, that the springs remain pressed, forming electrical connection and cannot move the armature 27 back until it is attracted by the electromagnet 28; this ensures proper connection and the armature will not get loose by shaking and jerking of the instrument. Some such arrangement is essential as unlike other switches there is no additional power to keep 29 properly closed when a current is to pass through it and which is required at the time of retracting the meter; the connection of 29 with 69 breaks only when the full attraction of the armature is effected.

When the receiver is lifted off its cradle 15 the retracting contact 105 is released by pin 7 disengaging from pin 7a fixed to the spring of contact 105. Pin 7a works in a slit 105a of the tube within which 105 works.

The contact 105 connects to contact 106 to 20 close the line circuit for a moment and then contact 105 retracts to its normal position.

During contact between 105 and 106 when the line is closed for a moment, the galvanometer 107 or other indicator in the line wire shows whether 25 the line of the subscriber is in order or not.

If the line is out of order, the subscriber must not push knob 17 to advance rod 16 as otherwise the meter will register a call for which he cannot expect retraction. Again adjustments are such that during reception of calls, 35 is closed before 105 touches 106, so that the ringing current may not pass through the indicator. In the case of automatic instruments however indicators are not essential.

It may further be noticed that the ringer 32 may also act somewhat as an indicator when the spring controlled retracting contact 105 functions, even if the indicator 107 is omitted. As will be realised, the line always remains connected with a battery and the ringer through a condenser remains connected with the line, and at this stage if "make" and "break" is effected by 105, a current of pulsating nature (which only can make the ringer respond) will be produced for a moment and the current will pass through the ringing circuit and two distinct sounds will be obtained for each rise of stem 2. The sound of the ringer will be a little short in intensity, as the pulsating current so generated is weaker than the usual ringing current adopted.

Additional safety devices are employed as follows:

(a) A device for preventing advancement of the meter through carelessness when the receiver is off the cradle and rod 16 pushed in the member 10 released i. e. during conversation for cutting calls.

The device is comprised by the spring strip 110 which as already stated is controlled by pin 109 fixed on rod 11a attached to the bottom of member 10.

The strip 110 enters a slot 111 in rod 16 when the latter after releasing the member 10 sets back to rest at its normal position, and thus the rod 16 is locked till the receiver is placed back on the cradle when strip 110 will be pushed down out of slot 111 by pin 109 so as to leave rod 16 released.

(b) A further device for preventing advancement of the meter through carelessness while conversation is going on during incoming calls by locking rod 16. The device comprises a lever 114 fixed to the axis 113 of lever 39 and rod 115 working in a bracket 118. When member 70

39 is moved to cause 37 to connect switch 35, lever 114 is also moved by the rotation of 113 and operates rod 115 and causes it to enter a slot 116 located in rod 16, thus locking rod 16 till 5 the receiver is placed back on the cradle. When the receiver is replaced, rod 37 and lever 39 move in the opposite sense until 113 and 114 cause rod 115 to drop out of slot 116, whereupon rod 16 is released.

10 The electrical connections are now mentioned with reference to the diagram.

The two line wires 70, 71 from the exchange are joined with two connectors Q1 and Q2 respectively inside the instrument. The wires 72, 73 of the cord from the receiver microphone handle are joined respectively with two other connectors Q3 and Q4 also inside the instrument are made with insulated wires. Q1 is connected by wire 74 to one end of the condenser 33. The other end of the condenser 33 is connected by wire 75 with one end of the ringer 32, and the same end of the condenser is also connected with one end of automatic control 34 by wire 76. The remaining terminals of 32 and 34, are 20 connected with Q2 by wires 77 and 78 respectively. Again Q2 is connected with Q3 by wire 79 and Q4 is connected by wire 80 with one end of switch 35, which end and switch 13, switch 63, switch 60, switch 51, switch 56, switch 23a, 25 switch 29, the meter-electromagnet 28 and Q3 are all connected in series by the wires 81. Switch 56 and switch 64 are connected in parallel by wires 97 and 98. The other end of switch 35 is connected by wire 95 and Q1, as well as by 30 wire 96 with one end of switch 51 as shown in the diagram. Also one end of switch 51 is connected by wire 90 with the pawl 53a and the other end of switch 51 is connected with the rod 48 by wire 91 as already stated. The line may 35 be joined up with the instrument by insulated wires and, unlike the present practice in such a manner that the instrument cannot be disconnected from the line without leaving signs of tampering.

40 45 The working of the instrument according to the invention is as follows:

When a call comes from outside to the subscriber, due to the usual manipulation at the switch board by the exchange operator, a ringing current will pass to the called subscriber's line; at this stage only the ringer 32 and the control 34 will function. Supposing the called subscriber is present and he lifts his receiver to attend to the call, the armature 36 being already attracted down and the pin 4 releasing the lever 39, the knob 31 jumps into the switch 35 which is thus closed and the line now comes to the phone circuit and 32 and 34 cease to function. At this stage the receiver is connected with the line thus:

Q1 i. e. wire 70 gets a connection with Q4 through the switch 35 and Q4 through the receiver-microphone connects to Q3 and then Q3 connects to Q2 by wire 79 and so to the other wire 71 of the line, and no other circuit of the instrument now functions. In this connection it will be further noticed that while receiving calls, the tapping contrivance cannot function, firstly because the phone circuit is completed independently of the contrivance, and secondly because the contrivance remains locked until calls are made as the called subscriber can have no occasion to attract the attention of the operator. When the conversation is over, the receiver is replaced on the cradle and the instrument re-

gains its previous position. Such receiving of calls can be made over and over again, in the same manner as described. From outside therefore, to a called subscriber, this instrument works in the same manner as the ordinary instruments.

Further, unlike the usual telephone, the exchange cannot be obtained by only lifting the receiver from the cradle 1. To give indication to the operator by the line-lamp the subscriber has got to press the knob 17 after removing the receiver. This will actuate the meter 23 in the instrument, and only then will the line lamp indication be possible when switch 13 is closed. When a call is to be made through the instrument, the first duty of the subscriber is to lift the receiver and if the indicator functions to then push the knob 17, whereby the pawl 25 will actuate the meter 23 thus counting a call and simultaneously the connecting knob 11 jumps to close the switch 13. At this point it will be noticed that knob 17 cannot be pushed to release the rod 14 until the receiver is lifted and the hole 6 comes into alignment with rod 16 to allow a longitudinal movement of the rod 16. This can only be effected when the maximum upward movement of the cradle stem is reached after the receiver is taken off. This maximum upward movement of stem 2 is controlled by a catch 59 fixed to the platform 8 to obstruct pin 5. The maximum downward movement of the said stem is reached when the receiver is replaced. Due to the closing of switch 13 the subscriber's line lamp at the exchange is lit and the attention of the exchange operator is drawn to it and the exchange operator attends to the subscriber in the usual way. The circuit that functions at this stage is Q₁ through switches 51, 60, 63, switch 13 and Q₄ and through the phone and receiver goes to Q₃ and so to Q₂ and thus the line is closed, as ordinarily the switches 51, 60 and 63 remain closed. Supposing the number asked for is not engaged and the party attends; the conversation goes on and when finished the receiver is simply replaced on the cradle, and the switch 13 is again cut-off and member 10 is locked by the rod 14. This is an instance of effective call and has been recorded beforehand and the same thing repeats for all effective calls.

But it is also possible that, whatever be the reason, the number wanted is found different from the number obtained which is an instance of "wrong connection," and the calling subscriber must get the right connection without any charge, i. e. without advancing his meter any more. In such case he will, without replacing his receiver, operate the rod 41 i. e. will push knob 52 to draw the attention of the operator and will simply ask for the right number; suppose the right number is available; the conversation is then carried on and when finished the receiver is replaced. Thus the right number is obtained without further charge although the connection was wrong. But if the right number is not available after all i. e. found "no reply" or "engaged," the meter reading will be stepped back a unit as will be presently explained. Now what takes place on pushing the rod 41 by knob 52 is that 47 is pulled out of the switch 51, breaking one of the two connections of switch 51 but maintaining the other connection i. e. the one formed by the contact of the pawl 53a with the lever 48 and the wires 90 and 91. Knob 52 is then further pressed, until a click is heard in the phone, when for a moment the switch 51 loses both its closing connections when the supervisory lamp will

be "on" and again "off" as soon as rod 41 springs back to close the switch 51. This can be repeated until the operator responds. At this point it will be noticed that breaking both the connections of the switch 51, i. e. keeping it open for more than a short period, is not within the power of the subscriber. Various methods can, however be adopted for this purpose. The provision of such a mechanism i. e. self-closing switch 51, is particularly necessary as otherwise any number of calls can be made without operating the meter.

The rod 41 when pushed can give indication by the supervisory lamp as already noted and when necessary it can give indication by the line lamp. That is, 41 can cause only a momentary interruption to the line when knob 52 is pressed.

It is also quite possible that the number asked for or the corrected number after wrong connection is found to be "no reply" or "engaged," both of which are ineffective calls. In this case the meter has already recorded the call as it does in cases of effective calls, although it is now found ineffective. Under the circumstances, if the indication for "no reply" or "engaged" which covers practically all of the ineffective calls, be given electrically, the subscriber whose call has become ineffective, will turn the knob 52 till it is locked by 65 when the meter will tick back one unit and then he will simply replace his receiver, whereby the instrument will be restored to its original position. What takes place during such retraction is that "busy-back" tone or tone signal goes on in the phone and turning the knob 52 at this stage has the effect of closing the switch 64 and consequently by wires 97, 98, the switch 56, and then breaking the contact of switch 63 as 65 drops into the recess 67, whereby the line gets connected with the meter, as Q₁ connects through the switch 64 to the meter and back to Q₃ i. e. Q₂ and the impulse compounding with the busytone as explained later sets it back by action of pawl 26 one digit. When the receiver is replaced, the lever 68 is pressed by pin 5 and one arm of 61 pulls up 65 and so rod 41 turns back, and the switch 63 becomes closed while switch 64 opens. Thus the retraction of the meter reading by a unit can be entirely independent of the exchange operator if the system of electrical indication is introduced for all other sorts of ineffective calls, in addition to "no reply" or "engaged" as mentioned above. It may be mentioned here, as already said, that some modification in the busy tone impulse may be necessary to suit the purpose of stepping back of the meter. The busy tone is supplied from the ringing machine and made to pass through a vibrator and the former makes the current intermittent and the latter vibrating; instead of the vibrator induction coils are also adopted for the said tone. During the supply of busy tone therefore, which is obtained several times the necessary retraction is to be effected, while the buzzing goes on in the receiver. But it is known that a vibrating current may not be very suitable for exciting the electromagnet of the meter sufficiently to give clear and effective pull to its armature, on which the stepping back of the meter depends. It can however be arranged for the current at the exchange instead of being made intermittent to be made continuous but alternately passed through the induction coil and connected directly to the line; and this alteration may be effected by the ringing machine. The result will be that the current in question, which will of course have suitable voltage to work

the meter, being direct, i. e. continuous, will produce no buzzing in the ear piece of the subscriber when the current is put on the line directly, i. e. not through the induction coil, and during this steady supply of current the retracting mechanism of the meter can be made to function quite effectively by the subscriber with the help of knob 52. This change however in the way of supplying the busy tone will apparently create no difference in its tone or character. The voltage of the current required for operating the meter may be higher than the direct current provided for any other purpose in the line. Under the automatic system however it can be easily arranged to supply the meter retracting impulse to the line say at intervals of say five seconds during all sorts of tone signals.

But if the system of oral information has to prevail, the operator will have to say "retract" and on getting this indication the subscriber will push 52 further in than is necessary for only flashing, and to do this he will have to exert a little heavier pressure when rod 41 reaches the flattened end of 55, as 55 is held by stronger spring. When 55 is thus pushed by 41, the knob 55a at the other end of 55 closes the switch 56 and 55 will be locked in that position by the lever 58, the latter at the same time also breaking the connection of switch 60. At this point it will be observed that the operator gets an indication in the supervisory lamp. By this the operator will understand that the line has been put into the meter circuit and then the operator will give an electric impulse from some continuous current source, to the line of the subscriber. The current will flow for example from Q1 to switch 56, and through switches 23a and 29, and through these to the electromagnet 28 of the meter 23, then to Q3 and so to Q2 which connects to the other line wire. It can be seen that when the meter circuit is connected to the line, the phone circuit is cut off at the switch 60 and this prevents any current, that may be necessary for retracting the meter, from passing into the ear-piece and making unnecessary noise in it. When the meter is retracted the armature 27 is attracted and as a result connection is broken at the switch 29 and the hammer 27a is caused to strike the gong 27b, thereby giving the subscriber a sound indication and the operator a lamp indication by the supervisory lamp, which latter may indicate to the operator that the meter has been actually stepped back. It should also be noted that the switch 29 ordinarily remains closed by the metal strip 69 fitted to the extension rod 270 of the meter armature 27, as during the actuating of the meter by pawl 25, the lever 31 pushes the extension rod to close the switch 29. In cases of ineffective calls, "no reply" and "engaged" etc., the meter can thus also be retracted by control of the operator.

As already stated, a lock is introduced into the instrument in order to render inoperative the whole mechanism inside the instrument, meant for outgoing calls, only leaving the instrument fit to receive calls. This lock comprises a key controlled bolt 120 and the desired result can be achieved by arresting the movement of the rod 16 while the instrument is at rest by causing the bolt 120 to engage recess or notch 121 in rod 16 to prevent rod 16 from being pushed in. On such locking of the rod 16 the switch 13 can not be closed and therefore calls cannot be made, but the switch 35 is not interfered with and therefore the reception of calls is quite possible, as on lift-

ing the receiver during ringing, the rod 37 will jump to close 35, as explained, giving a connection of the phone with the line.

After the meter is retracted the subscriber has only to replace the receiver on the cradle and the stem of the cradle coming down will restore the instrument to its original position, i. e. will cut off the switch 56 and engage the switch 60 by movement of the lever 61, lever 58 and knob 58a. Thus ineffective calls are eliminated when intimated orally and are controlled by the exchange.

It may be noticed that both in the case of oral and of electrical indications of ineffective calls when the meter is to be retracted the rod 41 can be turned, but it is better in the case of oral indication to push rod 41 as already detailed and for this reason namely that the operator may know whether the line is actually put into the meter circuit after the operator says "retract" as the supervisory lamp will be once "on" and "off." But in case of electrical indication it is always better to turn rod 41, firstly because there is no necessity of lamp indication to the operator and secondly because the line is not interrupted at all at switch 51 during transferring the line from the phone circuit to the meter circuit.

Regarding the telephone instruments that are used under automatic exchange, the present invention can be adapted in them to give greater facility to the public than at present, of course where call charge system prevails. The automatic instruments supplied to the subscribers consist of the usual set of instruments for C. B. working, with the addition of "calling" or "selector" apparatus for sending the requisite electrical impulse along the two wire lines for operating the mechanism at the central office. The selector mechanism or "dial" is mounted on the instrument. The dial is connected to the mechanism which, when operated for getting connection with some number of a subscriber by turning of the disc, causes, on its return, a number of disconnections to be made in the line circuit corresponding to the amount of turning. There are call registering meters at the exchange which can record calls automatically when the called subscriber attends, and there is no question of wrong connection if selecting is right. In the case of "no reply" or "engaged," tone signals are obtainable and these can be utilised for retracting meters in the manner hereinbefore described. But it may be noticed that some simplification of the mechanism here described is possible when included in telephone instruments under the automatic system. For example, the contrivance for drawing the attention of the operator is not required as there is no operator under the mechanical switching system, and so the switches 51 and 69 can be permanently closed and the knives of switch 56 also parts 43, 47, 58, and 55 as also the lower arm of lever 61 which controls lever 58, and longitudinal groove 42 can be omitted. Control 34 and parts that work in conjunction with it may also be omitted and the movement of the dial of the automatic instrument may be made subject to the same two conditions, as necessary in case of manual system sets, for the operation of switch 13. Instead of connecting and disconnecting switch 13, the metal piece 10 may release or fix the dial in the automatic instrument, the purpose of switch 13 being served in the existing way. In the automatic instrument although connection with the exchange is effected, by lifting the receiver still required number cannot be obtained until dialed and during

reception of calls simply the receiver is lifted and no dialing is required; so no extra arrangement, for reception of calls as control 34 and parts connected therewith, is required in the automatic sets and simply the dial can be made movable after the meter has been advanced 1 unit. It is however within the scope of this invention to construct one instrument which can be rendered serviceable in both manual and automatic exchange system and, for the latter, this can be done by closing when necessary the longitudinal groove 42 only i. e. by preventing the movement of rod 41 along its length, so that rod 41 can only be turned to cause the switches 63 and 64 to function.

It may be further possible for the sake of economy of space and ringing current to combine 32 and 34 as one unit. That is, the soft iron yoke 128 of the combined unit can be replaced by say brass and the cores can be a little more extended downward and a light soft iron armature such as 36 can be suitably fitted below it having no spring action, i. e. while the combined unit is at rest, the armature falls by its weight and can thus prevent the rod 37 from closing the switch 35 and when the combined unit works, the armature is drawn up and 37 is set free to close switch 35 when the receiver is off the cradle. For the working of the combined unit of course the pin 40 can be fitted to 37 so as to project upwardly. The said replacement by a brass yoke will slightly reduce the strength of the cores of the combined unit but that can be compensated for by providing a stronger or saturated inducing permanent magnet in it, in place of the usual inducing magnet. Slightly increased current strength will bring about a satisfactory result.

It is further within the scope of the invention to adopt locally a relay at the subscriber's end for supplying a sufficiently strong current for the retraction of the meter, if the current used for the purpose from the exchange is not sufficient or is not effective due to any reason.

The construction of switches can be of various types and the knobs or plates which connect up the switches are made of metal and these metal knobs or plates should be insulated from their respective holders so that other metal parts of the instrument cannot be electrified. It is also to be understood that the control 34 may be positioned in various convenient positions with the corresponding change of the necessary parts.

In place of locking the push rod, the switch connecting the instrument to the exchange for

outgoing calls may be locked directly by a lever lock or by other means.

This system can be adopted in wall and table types of instruments as well as in those instruments where the receiver is separated from the microphone and the former is suspended on a spring hook projecting outside the instrument; there the weight of the earpiece and consequently the movement of the hook may be utilised to serve all the functions of the cradle stem already explained, the hook comprising or being associated with, an equivalent part to the cradle stem. It is further possible to suitably fit up this invention to the existing types of sets as separate attachments.

Having now particularly described and ascertained the nature of my said invention and in what manner the same is to be performed, I declare that what I claim is:

1. In a telephone system the combination of a subscriber's telephone set including a transmitting and a receiver unit capable of being electrically connected to an exchange, a receiver, a support for the receiver, circuit closing means actuated by the receiver support adapted to connect and disconnect the unit with the exchange, a toll meter located in the unit for registering outgoing calls, manually actuated means for advancing the meter one digit after the receiver is raised to connect the unit with the exchange, a push rod having a switch closing member adapted to close a switch and adapted when closed to signal the exchange when a "call" is not completed through the exchange, said last mentioned means adapted to close a circuit, and means at the exchange for retracting the meter one digit through said closed circuit when the "call" through the exchange is not completed.

2. In a telephone system the combination of a subscriber's telephone set including a transmitting and a receiver unit, a receiver, a toll meter on the unit for registering the outgoing calls, means on the unit for advancing the meter one digit when the receiver is raised and means on the unit independent of the operation of the hand set for signalling the exchange when a "call" is not completed through the exchange, said last-mentioned means adapted to close a circuit and means at the exchange through said last-named circuit for magnetically retracting the meter one digit through said closed circuit when the call through the exchange is not completed.

AJOY KUMAR GHOSH.
